UNITED STATES PATENT OFFICE.

JOHN C. McLAUGHLIN, OF JERSEY CITY, NEW JERSEY, ASSIGNOR TO UNDERWOOD TYPEWRITER COMPANY, OF NEW YORK, N. Y., A CORPORATION OF DELAWARE.

TYPE-WRITING MACHINE.

1,171,391.

Specification of Letters Patent.

Patented Feb. 8, 1916.

Application filed July 1, 1913. Serial No. 776,753.

To all whom it may concern:

Be it known that I, JOHN C. McLAUGHLIN, a citizen of the United States, residing in Jersey City, in the county of Hudson and State of New Jersey, have invented certain new and useful Improvements in Type-Writing Machines, of which the following is a specification.

My invention relates to ribbon mechanism for typewriting machines, and particularly to machines provided with a plurality of ribbons adapted to be selectively vibrated over the printing point.

An object of the invention is to provide improved means for selectively setting the ribbon vibrating mechanism to vibrate either ribbon over the printing point on the platen.

A further object of the invention is to provide improved means for shifting the ribbon feed from one set of spools to the other.

The invention also comprises an improved form of automatic means for reversing the ribbon feed.

Two sets of ribbon spools are provided on which may be wound ribbons of different colors, each set comprising spools located in front of the platen on opposite sides of the printing point, and each ribbon extends longitudinally of the platen below the printing line and through a ribbon guide or vibrator, which is actuated from a universal bar each time a type bar is operated, and thereby vibrates the ribbon over the printing point. The two vibrators are connected through an intermediate member or shifting device, which is shiftable to bring either vibrator into operative position and simultaneously move the other vibrator to inoperative position. The vibrators and said shiftable device are moved up and down together as a unit, so that a single vibrator lever or actuator serves for both vibrators. Said unit is slidably mounted in a frame which supports a card-holding device, said frame being shiftable up and down with the platen. The vibrators are actuated by a vibrator lever mounted on a frame operated by the shift keys, so that said lever and with it the vibrators are shifted up and down with the platen, the vibrator lever having a vertical slot and pin connection with the universal bar frame to maintain an opera-

tive connection between said frame and lever when the lever is shifted.

Two sets of ribbon spools are selectively driven by a train of gearing extending from the carriage drum, and comprising vertically disposed shafts in swinging frames and carrying at their upper ends pinions which may be moved into driving engagement with gears on either set of ribbon spools. Said frames are swung to reverse the ribbon feed by means of a rock shaft and intermediate connections; said rock shaft also operates through intermediate devices to set the vibrators. The rock shaft is operated from a ribbon key which, at each succeeding depression, reverses the rock shaft; that is, when the key is depressed, the shaft is rocked in one direction and establishes a driving connection for feeding one set of spools and also moves the corresponding vibrator to active position. When the key is again depressed, the rock shaft is rocked in the reverse direction, thereby connecting the ribbon feed to the other pair of spools and also reversing the position of the vibrators. The ribbon feed mechanism for each ribbon is thus set for operation concomitantly with the setting of the vibrator for said ribbon, and conversely; and when either ribbon vibrator is silenced the feed for said ribbon is thrown out of gear. Both ribbons are threaded through a pair of swinging arms adapted to be operated by buttons on the ribbons for automatically reversing the ribbon feed, so that each arm can reverse the feed for either ribbon. Said arms operate through suitable mechanism to longitudinally shift a shaft of the ribbon feed mechanism, and thereby reverse the feed.

Other features and advantages will hereinafter appear.

In the accompanying drawings, Figure 1 is a sectional elevation of an Underwood machine modified in accordance with the principles of my invention. Fig. 2 is a detail section showing the ribbon vibrators and the means for shifting them up and down with the platen, the platen being in lower case position. Fig. 3 is a similar view with the platen shifted to upper case position. Fig. 4 is a front perspective view showing the ribbon mechanism. Fig. 5 is a detail

plan view of gears for selectively driving the ribbon spools. Fig. 6 is a detail plan view showing two of the ribbon spools and the ribbon guides and vibrators. Fig. 7 is 5 a detail elevation view showing mechanism for silencing the ribbon feed. Fig. 8 is a front elevation showing ribbon feed gearing and gear-shifting mechanism for selectively driving the ribbon spools, the means for dis- 10 connecting the gearing when the carriage rack is lifted, and other details of the invention. Fig. 9 shows some of the parts of Fig. 8, but with the rack elevated and the train of ribbon-guiding gears disconnected. 15 Fig. 10 is a sectional elevation showing the ribbon-vibrating mechanism, a space key, and connections from the space key for operating the escapement dogs. Fig. 11 is a part sectional rear elevation view of the ma- 20 chine, with parts broken away. Fig. 12 is a detail view of the means for automatically reversing the ribbon feed. Fig. 13 is a dis- 25 assembled view of parts of the reversing mechanism. Fig. 14 is a detail view illustrating the means for shifting the ribbon vibrators. Fig. 15 is a perspective view of the shifting bar shown in Fig. 14.

The type-keys 1 are mounted on levers 2 fulcrumed on a rod 3 and connected by bell- 30 cranks 4 to the type-bars 5 which are ful- crumed on a rod 6 and adapted to be thrown upward to bring the types 7 to the printing position in front of the platen 8. The platen frame 9 is mounted on a traveling carriage 35 10 operated in the usual manner by a spring drum 10^a connected through a band 10^b to the carriage. The travel of the carriage rotates an escapement wheel 11 and a pinion 12 in mesh with a rack bar 13 on the car- 40 riage. The rack bar may be supported on a swinging frame 14 pivoted at 15 and opera- 45 ble by a finger 16 to lift the rack bar free from the pinion 12. The letter-feed move- ment of the carriage is controlled by escape- 50 ment dogs 17 coöperating with the escape- ment wheel 11 and actuated by a projection 18 on a universal bar frame 19 comprising a universal bar 20. The latter is positioned and adapted to be operated in the usual man- 55 ner by shoulders 21 on the type-bars. The platen is shiftable to upper and lower case positions by means of a shift rail 22 on which runs a roller 23 on the platen frame. The shift rail is mounted on uprights 24 con- 60 nected at their lower ends to levers 25 fixed to a rock shaft 26 and adapted to be actu- 65 ated by shift key levers (not shown).

The invention provides means for selec- 60 tively feeding and vibrating two separate ribbons, which are preferably of different colors, as for example, black and red. One of these ribbons *r*, which for convenience will be referred to as the red ribbon, is mounted on an inner pair of ribbon spools 27 and 28, and the other ribbon *b*, which will

be referred to as the black ribbon, on an outer pair of spools 29 and 30. The ribbons ex- 70 tend through ribbon vibrators 31 and 32 which are located in front of the platen and are adapted to be vibrated upward to bring a ribbon over the printing point each time a type-bar is actuated. Each of these vibra- 75 tors comprises a pair of eyes 33 forming a guide through which the ribbon is threaded, a body portion with a vertical slot 34, and depending vertical arms 35 by means of which the vibrator is slidably mounted and guided in a frame 36.

The vibrators 31 and 32 are both slide- 80 up and down in the frame 36 to selectively bring them to operative position in the frame. A three-arm lever 37 interposed be- 85 tween the vibrators is provided with pins or projections 38 which enter notches 39 and 40 in the vibrators 31 and 32 respectively. The lever 37 is mounted on a pivot pin 41 which extends through the slots 34. Also connected to the pivot pin 41 is a depending arm 42 provided with an arc-shaped slot 43 concentric with the pin 41 and in which is 90 guided a pin 44 on the lever 37.

With the parts in the position shown in Fig. 11, the vibrator 32 is held in its low- 95 ered or inactive position while the vibrator 31 is in operative position, so that it may be vibrated over the printing point by mechanism presently to be described. The lever 37 is movable about its fulcrum 41 to carry the pin 44 from the Fig. 11 position to the opposite end of the slot 43 (Fig. 14), 100 thereby moving the vibrator 31 downward to inactive position and lifting the vibrator 32 into operative position. The means for shifting the lever 37 will be described later. It will be noted that the two vibrators, to- 105 gether with the intermediate lever 37 and the arm 42, are adapted to be moved up and down as a unit, independent movement of these parts being prevented except through the shifting of the lever 37. The actuating 110 means for vibrating this unit comprises a vibrator lever 45 in the form of a bell crank pivoted at 46 and having a forwardly ex- 115 tends arm connected at 47 to the lower end of the arm 42, so that when the lever 45 is vibrated the vibrators are moved up and down. An upwardly extending arm 48 of said lever carries a wrist pin 49 working in a vertical slot provided in a depending bracket arm 50 on the universal bar frame 120 19. When a type bar is actuated, the universal bar frame is moved rearwardly, and through the lever 45 moves the ribbon vi- 125 brators upward, to bring the uppermost or operative vibrator over the printing point so that the type will strike through the ribbon onto the work-sheet. The operating lever 45 is mounted on a frame 51 which is adapted to be shifted up and down with the platen. This frame carries at its lower end 130

135

a roller 52 seated in the bifurcated end of a rock arm 53 fixed to the rock shaft 26 so that when a shift key is depressed to rock the shaft 26 and lift the shift rail 22, the frame 51 is also lifted, said frame being guided on a stationary vertical rod 54. It will thus be seen that when the platen is shifted from lower case position (Fig. 2) to upper case position (Fig. 3), the vibrators are also shifted so that their position relative to the platen is substantially unchanged. The frame 51 is provided with an upwardly extending arm having a slot 55 to receive a ledge 56 on the frame 36 so that the latter is shifted up and down with the vibrators. On said frame 36 is mounted a card holder 57 which may be made of wire and suitably shaped to hold a card in printing position on the platen. As the card holder 57 is shiftable with the platen, the danger of the card or work-piece being pulled out of position as the platen is shifted, is avoided.

The means for selectively shifting the ribbon vibrators to operative position will now be described. A ribbon key 58 which, in the form of the invention shown, is located near the right-hand end of the machine, is mounted on a lever 59 fulcrumed at 3 and connected through an arm 60 to a plate or draw-bar 61 formed with a vertical slot 62 through which extends a rock shaft 63. Fixed to the rock shaft is a sleeve 64 from which extend arms 65 carrying pins 66 in position to be actuated by a pawl 67 in the form of an inverted V pivoted at 68 to the draw-bar 61. The end of each arm of the member 67 is somewhat concave, or formed with a notch 69 which prevents said member from slipping off the pin 66 and also serves to cam said member about its pivot, to permit said member to coöperate with either pin 66 without interfering with the other pin.

The construction just described permits the shaft 63 to be rocked alternately first in one direction and then in the other, as the ribbon key 58 is repeatedly depressed. For example, as indicated in Fig. 8, the ribbon key has been depressed and the shaft 63 rocked in a clockwise direction to bring the right-hand arm 65 to a substantially horizontal position, and the left-hand arm 65 to an upwardly-inclined position. When the key has been released the pawl 67 is moved upward, and upon the next succeeding depression of the key the left-hand pin 66 will be engaged by the corresponding arm of the pawl 67. The cam surface 69 on the left-hand arm of the pawl when it engages the pin 66, swings the pawl to the left sufficiently to clear the right-hand pin 66, and a continued downward movement of the pawl 67 rocks the shaft 63 in a counter-clockwise direction. When the ribbon key is again depressed, the right-hand pin 66

will again be engaged by the pawl 67 and the rock shaft 63 returned to the Fig. 8 position. Fixed to the rear end of the rock shaft 63 is an arm 70 carrying a wrist-pin 71 which works in a slot 72 in the lower end of a lever 73 connected by a pivot pin 74 to a bracket or support 74^a on the machine frame. The pivot 74 may extend through a slot 75 in the arm 70 to permit said arm to swing. The upper end of the lever 73 has a slot and pin connection with a slide bar 76 which may be supported and guided on the carriage shifting rail 22 by means of shouldered screws 77 extending through slots 78 in the slide bar and threaded into the guide rail 22. The inner end of the slide bar 76 has a forwardly extending arm terminating in vertical fingers 79, between which extends the pin 44 of the three-arm lever 37.

As shown in Fig. 11, the vibrator 31 and the black ribbon *b* are in operative position, the red ribbon *r* being silenced. To reverse the vibrators, the ribbon key 58 is depressed carrying with it the pawl 67, and the left-hand arm of said pawl, as viewed in Fig. 11, engages its pin 66 and rocks the shaft 63 to the left, thereby swinging the lower end of the rock arm 70 to the right as shown in Fig. 14. This movement of the arm 70 rocks the lever 73 about its pivot 74 and moves the slide 76 to the left (Fig. 14), thereby rocking the three-armed lever 37 from the Fig. 11 position to the Fig. 14 position, thus reversing the vibrators and bringing the vibrator 32 and the red ribbon to active position. The two ribbons may both be silenced by rocking the shaft 63 to an intermediate position, which is preferably done by means of a lever 80 connected by a pivot 81 to a stationary arm 82. The lever 80 carries a pin 83 which, when the lever is moved to the left from Fig. 4 position to Fig. 7 position, engages a cam arm 84 fixed to the sleeve 64, and thereby cams the sleeve and with it the shaft 63 to an intermediate position. The vibrators are thus brought to an intermediate position so that when the type-bars are operated, neither ribbon is lifted high enough to cover the printing point. The slide 76 is yieldingly held in any one of its three positions of adjustment by a spring 85 (Fig. 15), the end of which engages notches 86 positioned to correspond with the different adjustments of the vibrators. The ribbon spools are removably mounted on spindles 87 to which are secured gears 88, 89, 90 and 91. Between the gears 88 and 90 is a driving pinion 92 mounted on the upper end of a vertical shaft 93 journaled in a swinging standard or support 94 connected at its lower end by a pivot 95 to a stationary support. On the lower end of the shaft 93 is a beveled pinion 96 adapted to mesh with a gear 97 on a horizontal shaft 98. Between the gears 89 and 91 is a

is a pinion 99, likewise mounted on a shaft 100 journaled in a swinging upright 101 pivoted at 102, said shaft having a pinion 103 in mesh with a gear 104 on the shaft 98. 5 Loosely mounted on the shaft 98 is a barrel pinion 105 having a one-way driving connection with the shaft 98 by means of a pawl 106 on a sleeve 107 secured to the shaft. A shaft 108 carries a worm gear 109 in mesh 10 with the pinion 105. On the rear end of the shaft 108 is a gear 110 in mesh with a pinion 111 driven by a gear wheel 112, which is preferably fixed to the spring drum 10^a which drives the carriage. The pinion 111 is carried on an arm of a lever 113 mounted 15 on the shaft 114 of the spring drum and having a projection 115 extending over the rack bar 13. The pinion 111 is in rolling contact with the gear 112 and when the rack bar 13 20 is lifted out of mesh with the escapement pinion 12, either by the release key 16 or by the operation of one of the tabulator keys, which may be employed and which may be connected in the usual manner to lift the 25 carriage rack 13, the pinion 111 is moved away from the gear 110 and thereby disconnects the ribbon feed mechanism from the driving motor.

As shown, for example, in Fig. 4, the 30 shiftable pinions 92 and 99 are in engagement with the gears 90 and 91 for the outer or black ribbon spools, so that the black ribbon will be fed during the letter-feed travel of the carriage. Said pinions 92 and 99 are 35 shiftable into mesh with the inner gears 88 and 89 for the red ribbon spools by the following mechanism: A bar 116 is connected at one end by a pivot 117 to the swinging frame 94, the opposite end of said 40 bar being connected by a pivot 118 to a lever 119 loosely mounted on the shaft 63, the upper end of said lever being connected through a link 120 to the swinging frame 101. The bar 116 has an offset arm 121 pivoted to a rock arm 122 fixed to the rock shaft 63. When the shaft 63 is rocked by operating the ribbon key, the bar 116, with the connections just described, is moved to the 45 right (Fig. 4), thereby moving the swinging frame 94 to the right, and moving the pinion 92 into mesh with the gear 88. The movement of the bar 116 to the right also operates through the lever 119 and link 120 to move the pinion 99 into mesh with the 50 gear 89. It will be seen that the depression of the ribbon key operates to simultaneously reverse the ribbon vibrators and transfer the ribbon feed drive from one set of spools to the other so that the ribbon which is being 55 fed will always correspond to the vibrator which is in active position. The gear 110 is carried by a sleeve 123 loose on the shaft 108. A disk or flange 124 on said sleeve carries a pawl 125, which drives a 60 ratchet 126 secured to the shaft 108, a one-

way driving connection thereby being provided between the carriage driving spring and the shaft 108, so that during the return of the carriage, the pawl 125 rides idly over the ratchet 126 and the ribbons remain stationary. A gravity pawl 127 coöperating 70 with a ratchet 128 on the shaft 108, locks said shaft against backward rotation.

The gears on the ribbon spool spindles, when disconnected from the driving mechanism, are locked against rotation in either direction by dogs 148, (see Fig. 5) on a swinging frame 149 pivoted at 150 and operated by a pin 151 on the frame 94; said pin extending through an opening in the frame 149. When the pinion 92 is in mesh with the gear 88, the left-hand dog 148 locks the gear 90, and when the pinion 92 is swung into engagement with the gear 90, the frame 149 is reversed to lock the gear 88 and release the gear 90. A similar locking device is provided in connection with the gears 89 and 91. When the lever 80 is moved to the left (Fig. 7) to silence the ribbon vibrators, the ribbon feed mechanism is also silenced 90 by means of a pin 129 on the lever 80 riding on a cam 130 on a lever 131 and thereby swinging the latter on its pivot 132 and lifting the forward end of the shaft 108 to separate the gears 105 and 109. The shaft 98 95 is shiftable longitudinally to bring it into driving connection with either of the upright shafts 93, 100, to control the direction in which the active ribbon is fed, and is yieldingly held in either position to which 100 it may be shifted by a beveled disk 133 which moves with the shaft to either side of a holding disk 134 on a lever 135 pivoted at 136 and held by a spring 137 in contact with the disk 133. 105

The shaft 98 may be shifted by a hand crank 138 fixed on the end of the shaft, and which may also be used for winding the ribbons by hand. Mechanism for automatically reversing the feed of either ribbon is 110 provided as follows: Near each end of the shaft 98 is an arm 139 pivoted at 140 and provided at its upper end with slits or eyes 141 through which the ribbons are threaded. On the lower end of the arm 139 is a detent 115 142 adapted to be swung into engagement with a toothed wheel or disk 143 loose on the shaft 98. On the outer face of the wheel 143 are cams 144 coöperating with correspondingly shaped cams 145 having a fixed 120 connection to the shaft 98. The cams 145, at the end of the shaft, are connected to the crank 138 as is shown in detail in Fig. 13. A coil spring 146 is connected at its opposite 125 ends to the cams 144 and 145, and tends to hold them together and may also limit their relative rotation. The ribbons are provided near their ends with buttons 147 which actuate the arms 139, see Fig. 12. When the winding of a ribbon on one spool is about 130

completed, a button 147 engages an arm 139 adjacent the empty spool and swings said arm inward to bring the detent 142 against the disk 143. The disk being thus held 5 against further rotation and the cams 145 continuing to rotate with the shaft 98, said shaft is cammed in the direction of its axis, and thereby reverses the ribbon feed, that is, the empty spool is now connected to the 10 shaft 98 and the other spool is released. As both of the ribbons are guided through the same reversing arms 139, the same mechanism serves to reverse the feed of either ribbon. The escapement mechanism is operated from the space bar 152, as shown in Fig. 10, through the medium of a rock shaft 153, rock arm 154, link 155 and slide 156. On said slide is an offset 157 which swings the frame carrying the escapement dogs 17, 15 when the space bar is depressed. It will be noted that the ribbon vibrators are not actuated by the space bar.

Variations may be resorted to within the scope of the invention, and portions of the 25 improvements may be used without others.

Having thus described my invention, I claim:

1. In a typewriting machine, the combination of a shiftable platen, a card holder, 20 a frame therefor, means to shift said frame up and down with the platen, the position of the card holder relative to the printing point being substantially constant during the platen-shifting and the printing operations, and a ribbon vibrator mounted to 35 vibrate in said frame.

2. In a ribbon vibrating mechanism, the combination of a vertically disposed arm, a three-armed lever pivoted thereto, a vibrator 40 having a slot and pin connection to said lever at one side of its pivot, and a second vibrator having a slot and pin connection on the other side of said pivot, said vertical arm having a slot concentric with said pivot, 45 and said lever having a pin working in said slot.

3. In ribbon vibrating mechanism, the combination of a vertically disposed arm, a three-armed lever pivoted thereto, a vibrator 50 having a slot and pin connection to said lever at one side of its pivot, a second vibrator having a slot and pin connection on the other side of said pivot, said vertical arm having a slot concentric with said pivot, 55 said lever having a pin working in said slot, mechanism to move said lever about its pivot to selectively project the vibrators into active position, and means to reciprocate said arm, lever and vibrators as a unit.

60 4. In a typewriting machine, the combination of a shift key lever, a rock shaft operated thereby, an arm on said shaft, a vertically movable frame connected to said arm, a vibrator lever pivoted to said frame, a 65 universal bar, a vibrator, means to connect

one arm of the vibrator lever to the vibrator and the other arm to the universal bar, and a guide frame for the vibrator connected to said vertically movable frame to move up and down therewith.

5. The combination in a typewriter, of a shiftable platen, a frame connected to shift with the platen, a vibrator lever mounted on said frame, a vibrator connected to said vibrator lever, means to operate said vibrator lever, a second frame in which the vibrator is slidably mounted, a card-holding device mounted on said second frame, and a connection between said frames whereby the card-holding device is shifted up and down 80 with the platen.

6. In a typewriting machine, the combination of a carriage, a platen thereon, a shift rail, a slide bar mounted on said rail to shift up and down therewith and slidably longitudinally thereof, a ribbon vibrator, a shifting device between said slide bar and vibrator for shifting the vibrator into and out of operative position, and means for operating said slide bar.

7. In a typewriting machine, the combination of a platen frame, a platen, a shift rail on which the platen travels, a slide bar having a slot and pin connection with the shift rail for shifting the slide bar with the 95 shift rail and permitting said bar to slide on the shift rail, a ribbon vibrator, a connection between the vibrator and slide bar for shifting the vibrator into and out of operative position, and means for actuating 100 the slide bar.

8. In a typewriting machine, the combination of a platen frame, a platen, a shift rail on which the platen travels, a slide bar having a slot and pin connection with the 105 shift rail for shifting the slide bar with the shift rail and permitting said bar to slide on the shift rail, a ribbon vibrator, a connection between the vibrator and slide bar for shifting the vibrator into and out of 110 operative position, a rock shaft, connections between the rock shaft and slide bar, and a finger key connected to rock said shaft.

9. In a typewriting machine, the combination of ribbon vibrators; ribbon-feed mechanisms; a rock shaft; means operated by said rock shaft for bringing said feed mechanisms alternately into effective position and for alternately moving the vibrators to effective position; a ribbon-selecting key; and 115 means for causing successive operations of said key to rock said shaft alternately in opposite directions and thereby bring the ribbons alternately into activity.

10. In a typewriting machine, the combination of a rock shaft; a key; means for causing successive operations of the key to rock said shaft alternately in opposite directions; mechanism for alternately feeding a plurality of ribbons; vibrators for said rib- 125 130

- 6
- bons; and means operated by said rock shaft to shift the feeding operation from one ribbon to the other, and to bring into activity the vibrator corresponding to the ribbon being fed.
5. 11. In a typewriting machine, the combination of a rock shaft; a key; means for causing successive operations of the key to rock said shaft alternately in opposite directions; a plurality of ribbon vibrators; a connector between the vibrators for shifting the vibrators alternatively to operative position, and vibratable as a unit with said vibrators; ribbon-feeding mechanism; and means operated by said shaft to shift the ribbon feed from one ribbon to the other and reverse the said connector to bring to operative position the vibrator corresponding to the ribbon being fed.
10. 12. In a typewriting machine, the combination with two pairs of ribbon spool spindles, of gears on said spindles, shiftable pinions each located between two of said gears, shiftable frames carrying said pinions, a bar pivoted to one of said frames, a lever connected to said bar, a link connecting the lever to the other of said frames, a rock shaft to which said lever is fixed, a key, means for causing successive operations of the key to rock said shaft alternately in opposite directions and thereby shift the ribbon feed from one set of spools to the other, ribbon vibrators, and a shifter operated by said rock shaft to shift the vibrators and bring into activity the vibrator corresponding to the active ribbon spools.
15. 13. In a typewriting machine, the combination, with two pairs of ribbon spool spindles; of gears on said spindles; shiftable pinions each located between two of said gears; shiftable frames carrying said pinions; a bar pivoted to one of said frames; a lever connected to said bar; a link connecting the lever to the other of said frames; a rock shaft to which said lever is fixed; a key; mechanism between said key and rock shaft for rocking the latter first in one direction and then in the other direction, when the key is repeatedly operated, and thereby causing the rock shaft to reciprocate said bar and shift said pinions into operative relation to the two pairs of spools alternately; vibrators for the ribbons; and means operated by said rock shaft to bring into activity the vibrator corresponding to the active ribbon spools.
20. 14. In a typewriting machine, the combination with a platen shiftable to upper and lower case positions, of a card holder shiftable with the platen, a supporting frame for said holder, a ribbon vibrator mounted to reciprocate in said frame, and means to shift the ribbon vibrator with the platen.
25. 15. The combination with a platen shiftable to upper and lower case positions, of ribbon vibrators, a frame shiftable with the platen and in which said vibrators are slidably mounted, a device for changing the relative positions of the vibrators in said frame to bring either vibrator to operative position, and a card-holding device mounted on said frame to shift with the platen.
16. In a typewriting machine, the combination of a shift key lever, a frame shiftable vertically by said lever, a vibrator lever pivoted to said frame, ribbon vibrators operated by said vibrator lever to vibrate ribbons over the printing point, and a guide frame in which said vibrators are supported and guided during their vibrations, said guide frame connected to the first-mentioned frame to shift up and down therewith.
17. In a typewriting machine, the combination of a shift key lever, a vertically shiftable frame operated by said lever, a vibrator lever pivoted to said frame and comprising a forwardly extending arm, a ribbon vibrator connected to said arm, to vibrate a ribbon over the printing point, a universal bar frame, said vibrator lever having an upwardly extended arm connected to said universal bar frame, a guide frame in which said vibrator is guided during its vibrations, and a connection between said guiding frame and said first-mentioned frame to cause the frames to move up and down together.
18. In a typewriting machine, the combination with a plurality of pairs of ribbon spools, of a shiftable platen, a pair of ribbon vibrators in which the ribbons are guided and by which the ribbons are vibrated over the printing point, a shifter between said vibrators shiftable to move either vibrator to active position and concomitantly move the other vibrator to inactive position, a vibrator lever connected to vibrate said vibrators and shifter as a unit, said vibrator lever shiftable up and down with the platen and carrying said vibrators up and down with the platen, a key to operate the shifter and reverse the ribbon vibrators when the key is actuated, a motor, a gear train between the motor and the ribbon spools, means operated by said key to shift the gears of said train and thereby shift the drive from one ribbon to the other, a silencer, means operated thereby to prevent the ribbons from being vibrated over the printing point, and means operated by said silencer to interrupt said gear train, thereby to disconnect the motor from the spools.
19. In a typewriting machine, the combination with a plurality of pairs of ribbon spools, of a shiftable platen, a pair of ribbon vibrators in which the ribbons are guided and by which the ribbons are vibrated over the printing point, a shifter between said vibrators shiftable to move either vibrator to active position and concomitantly move the other vibrator to inactive position, a vi-

brator lever connected to vibrate said vibrators and shifter as a unit, said vibrator lever shiftable up and down with the platen and carrying said vibrators up and down with the platen, a key to operate the shifter and reverse the ribbon vibrators when the key is actuated, a motor, a gear train between the motor and the ribbon spools, and means operated by said key to shift the gears 10 of said train and thereby shift the drive from one ribbon to the other.

20. The combination with a platen shiftable to upper and lower case positions, of ribbon vibrators, a device connecting the vibrators and operable to bring either vibrator into activity and concomitantly repress the other vibrator, means to vibrate said connecting device and vibrators as a unit to vibrate ribbons over the printing 20 point, a frame stationary during the ribbon vibration and in which said vibrators and connecting device are mounted to vibrate, and means to shift said frame, connecting device and vibrators with the platen as the 25 latter is shifted to upper and lower case positions.

21. The combination with a platen shiftable to upper and lower case positions, of ribbon vibrators, a lever carrying the vibrators, means to operate said lever about its pivot to alternatively shift the vibrator to active position, a carrier for said lever, a vibrator lever connected to vibrate said carrier and thereby vibrate the ribbons, means 35 for shifting the vibrator lever with the platen, whereby the relative position of the platen and vibrators is substantially unchanged by the shifting of the platen, a frame in which the vibrators are guided and 40 supported, and means to shift said frame with the platen.

22. The combination with a carriage, of a platen frame and platen shiftable thereon to upper and lower case positions, a platen-shifting frame, a second frame separate 45 from the platen-shifting frame, a work-piece holder mounted on said second frame, means separate from the platen-shifting frame for shifting said holder and its frame when the platen is shifted, to maintain the 50 position of the holder relative to the platen substantially constant as the latter is shifted, a ribbon vibrator mounted to vibrate in said second frame, an actuator for said vibrator, and means to shift said actuator with the platen.

23. In a typewriting machine, the combination with a platen, a platen-shifting frame, and means operable to shift the platen frame and platen to upper and lower case positions, of a ribbon vibrator, an actuator therefor, and a support on which said actuator is mounted, said support being 60 separate from the platen-shifting frame, and operable by said platen-shifting means

to shift the actuator and ribbon vibrator as the platen is shifted.

24. The combination with a platen, a platen-shifting frame, and means operable to shift the platen frame and platen to upper 70 and lower case positions, of ribbon vibrators, a ribbon-selecting device operable to selectively shift the vibrators to active position, an actuator for vibrating the active vibrator over the printing point, a support in which 75 said actuator is mounted, a stationary guide for said support, said support being separate from the platen-shifting frame, and means for causing said support to be shifted by said platen-shifting means.

25. The combination with a platen and a platen-shifting frame, of ribbon vibrators, a ribbon-selecting device by which said vibrators are carried, said device vibratable with the vibrators and also shiftable to 85 bring either vibrator into activity; a slide bar mounted on the platen-shifting frame and shiftable longitudinally thereof to operate said selecting device, and a key for operating said slide bar.

26. The combination, in a typewriting machine, of ribbon mechanism comprising a plurality of ribbon vibrators, a key, means operated thereby to silence the active vibrator and bring the other vibrator into activity at each operation of the key, whereby 95 either ribbon may be vibrated over the printing point, and a ribbon-silencing key operative to silence the active ribbon vibrator and thereby prevent either ribbon from being vibrated over the printing point.

27. The combination, in a typewriting machine, of ribbon mechanism comprising a plurality of ribbon vibrators, a key, means operated thereby to silence the active vibrator and bring the other vibrator into activity at each operation of the key, whereby 105 either ribbon may be vibrated over the printing point, a ribbon-silencing key operative to silence the active ribbon vibrator and thereby prevent either ribbon from being vibrated over the printing point, mechanism for feeding the active ribbon, and means operated by said ribbon-silencing key to silence the ribbon-feeding mechanism when the vibrators are silenced.

28. In a typewriting machine, the combination with a carriage and a motor to drive the carriage, of pairs of ribbon spools; means for driving said spools from the motor comprising a spool-driving shaft, a gear train between the motor and said shaft, and means separate from said gear train and said driving shaft forming a driving connection between said driving shaft and the ribbon spools and shiftable from driving relation with a spool of one pair into driving relation with a spool of the other pair, whereby the ribbon feed is shifted from one spool to the other; and a key operable to 110 120 125 130

disconnect said driving shaft from the motor, whereby the feed of both ribbons is prevented.

29. In a typewriting machine, the combination with a carriage and a motor to drive the carriage, of pairs of ribbon spools; means for driving said spools from the motor comprising a spool-driving shaft, a gear train between the motor and said shaft, and 5 means separate from said gear train and said driving shaft forming a driving connection between said driving shaft and the ribbon spools and shiftable from driving relation with a spool of one pair into driving relation with a spool of the other pair, whereby the ribbon feed is shifted from one spool to the other; a key operable to disconnect said driving shaft from the motor, whereby the feed of both ribbons is prevented; ribbon vibrators individual to the ribbons; and means 10 operated by said key to silence the ribbon vibrators.

30. The combination with vibrators for individually vibrating a plurality of ribbons, and means for individually feeding the ribbons, of a key operable at each operation to silence the active vibrator and bring 15 into activity the other vibrator; said key also operable to silence the feeding means for the active ribbon and bring into activity the feeding means for the other ribbon, whereby, at each succeeding operation of 20 said key, the vibrating and feeding means

for one ribbon are repressed, and the feeding and vibrating means for the other ribbon are brought into activity, and a second key operable to silence the active vibrator without bringing the other vibrator into activity, and also to silence the ribbon-feeding means for the active ribbon without bringing 35 into activity the means for feeding the other ribbon.

31. In a typewriting machine, the combination with two pairs of ribbon spool spindles, of gears on said spindles, shiftable 40 pinions each located between a gear of one pair and a gear of the other pair of spindles, a key, means for causing each operation of the key to shift said pinions each from one to the other of the gears between 45 which it is located and thereby shift the ribbon feed from one pair of spindles to the other, ribbon vibrators, a connector between the vibrators for shifting them alternatively to operative position and vibratable as a 50 unit with the vibrators, and a shifter operated by said key at each operation of the latter to shift said connector and thereby bring into activity the vibrator corresponding 55 to the active pair of ribbon spool spindles.

JOHN C. McLAUGHLIN.
